Atlys.

UNITED STATES PATENT OFFICE.

HARVEY F. MARANVILLE, OF AKRON, OHIO, ASSIGNOR TO THE MILLER RUBBER COMPANY, OF AKRON, OHIO, A CORPORATION OF OHIO.

CORE.

Application filed March 9, 1923. Serial No. 624,083.

To all whom it may concern:

Be it known that I, HARVEY F. MARANVILLE, a citizen of the United States, and resident of Akron, in the county of Summit 5 and State of Ohio, have invented certain new and useful Improvements in Cores, of which the following is a specification.

My present invention relates to improvements in cores or formers designed for use 10 in the building of tires and more particularly such as are subsequently vulcanized on air bags.

The invention aims to provide a simple, economical and efficient construction which 15 may be easily operated, and which will be durable in use.

With these and other objects in view, the invention comprises the novel features of construction and arrangement and combination 20 of parts hereinafter described, the nature and scope of my invention being defined and ascertained by the claims appended hereto.

An embodiment of the invention is illustrated in the accompanying drawings in which:-

Figure 1 is a front elevation of a former constructed in accordance with my invention.

Fig. 2 is a transverse vertical section.

Fig. 3 is a detail view of handle and link connection.

Fig. 4 shows the hub and arms in side and end elevation.

Fig. 5 shows the locking ring in side and end elevation partly in section.

Fig. 6 is a sectional detail showing the connection between one of the arms and the core members (4 and 6).

Fig. 7 shows side and front elevation of the carrying shaft bushing, and

Fig. 8 shows the retaining ring in edge and side views.

Referring by reference characters to these drawings, the numeral 1 designates a hub member which is provided with spokes or arms 2 and 3, which support at their outer ends a segmental or arc-shaped core section 4, which may be of the ordinary or any desired exterior configuration when viewed in cross section.

The arms are provided with offset portions which are connected to the core section and these offset portions are preferably

formed in the shape of independent members or brackets 2^a and 3^a which have portions α secured by tap screws or other suitable means to the outer ends of the arms.

The brackets have laterally extending portions α' which in turn carry portions α^2 of flat or web shape, which extend radially outward and are connected to the core sections 4 by entering grooves 4^a cut in the ends of the core sections and being pinned therein as shown, by pins α^3 passing through 65 the web and through lugs, on the core sections.

Core sections 5 and 6 are hinged to the opposite ends of the section 4 so as to be capable of being swung inward in the plane 70 of the core. My preferred form of hinge is formed by making the webs α^2 wide enough to project beyond the ends of the core section 4 and enter grooves formed in the ends of said sections 5 and 6, said sections being 75 hinged to the webs by means of pins 7 and 8 passing through the webs and through the spaced ears or lugs 5^a and 6^a which lie on opposite sides of the web.

Preferably the angle iron formed by the 80 parts α and α' is braced by a web portion α^5 . A fourth section 9 is provided to complete the circular shape of the core or former, and this section constitutes a key section, the lines of juncture between the 85 ends of this section and the adjoining ends of sections 5 and 6 being non-radial, and preferably slightly flaring inwardly to permit the ready withdrawal of the key section.

This section is wholly detachable, being 90 intended to be placed in position and withdrawn by hand, and to insure its being held in perfect alignment with the adjacent sections, the abutting ends are provided with interlocking tongues and grooves, as is 95 customary in tire cores. For holding the key section against radial movement when in place between the ends of the adjoining hinged sections, said key section is provided with a bifurcated bracket 10 extending inwardly towards the axis of the hub, which is provided with handles 11 and 12 designed to be grasped by the operator to enable him to readily remove and replace the key section.

During the building of the tire, the key section is held against radial displacement relative to the adjacent sections, by a link

member, or strut 13, which has its inner ends pivoted between lugs 14 on the hub by means of pivot pin 14^a.

One of the handles (11) is rigidly connected to lug 10 in any suitable manner, as by having a threaded portion 11^a tapped into the lug from one side, while the other handle is preferably utilized as a locking means for connecting the outer end of the 10 link or strut to the lug 10. This is accomplished by providing a hollow bushing 12^a having a threaded portion tapped into an opening in the lug, the bushing having a stop collar 12^b and a segmental flange 12^c, 15 and having a reduced bore at its outer end forming an internal shoulder 12^d. The handle is recessed at its inner end to receive the outer end of the bushing and has a reduced bore which receives the outer end of a pin 20 or rod 12^e which is secured thereto in any suitable manner, as by riveting.

A spring 12^f surrounds the pin or rod 12^e, its inner end bearing against an annular flange *e* on the rod 12^e, while its outer end 25 bears against the shoulder formed by the reduced outer portion of the bore of the bushing. The spring is thus held under compression and tends to press the locking pin inwardly or to the left, Fig. 1, to cause its 30 free end to engage an eye or opening in the free end of the link or strut 13, (Fig. 1).

One-half of the inner end of the handle is cut away as indicated at 12^g so that in one position of the handle the cut away portion 35 lies opposite the segmental flange 12^c and the handle is free to be moved inwardly by the spring to cause the locking pin to enter the eye of the strut, but when the handle is pulled out and given a partial turn, the pin 40 will be held in unlocked position by reason of engagement of the segmental inner end of the handle with the segmental flange 12^c, as shown in Fig. 3.

The hub may be rotatably mounted upon 45 any suitable support, which, as it forms no part of the present invention, is represented by the broken shaft 20. I prefer, however, to provide a detachable connection between the hub and carrying member by which the 50 hub will be firmly locked to the shaft during operation, but may be readily removed to enable another core or mandrel to be substituted for the one previously carried thereby.

To this end I provide the hub with a 55 central bore 1^a, preferably tapered or flared in part, to cooperate with a bushing 15 permanently carried by the end of the shaft or spindle 20. Hub 1 and bushing 15 are provided with cooperating flanges 1^b and 15^b, 60 one of these parts, 15^b for example, carrying dowel pins 15^c which cooperate with dowel openings 1^e in the other part. A flanged ring 16 is rotatably mounted on the flange 15^b and retained thereon by a retaining ring

17, and may be provided with a convenient operating handle indicated at 16^a. The locking ring is provided with inwardly projecting spaced radial lugs, or segmental flanges 16^b (Fig. 5) equi-distantly arranged 70 and designed to cooperate with similar locking lugs 1^d (Fig. 4) carried by the flange 1^b of the hub, and it will be seen that when the hub has been placed with its flange 1^b against the flange 15^b, a partial rotation of 75 the locking ring will cause the lugs 16^b thereof to overlie the lugs 1^d and hold the parts firmly together against axial displacement, circumferential displacement being prevented by the dowel pins above referred 80 to. When it is desired to remove the core, it is only necessary to impart a reverse rotation to the locking ring, bringing the lug 16^b in alignment with the spaces between 85 the lugs 1^d.

In order to take up any looseness in the connections, when the parts are in interlocking engagement, and hold the hub firmly in place, I provide a plurality of clamping bolts 18^a which pass through the ring 16 approximately centrally of the lugs 16^b and through elongated peripheral recesses 15^f in the flange 15, the portions of the ring overlying the flange 1^b being preferably thickened or projected inwardly, as indicated at 95 16^f. Bolts 18^a are provided with cylindrical nuts 18 having operating handles 18^b, and the nuts are designed to pass through semi-circular recesses 17^a in the locking ring 17 and thus bear against the outer or left-hand face (Fig. 2) of flange 15^b and draw the parts firmly together, taking up any looseness and preventing rotation of the locking ring by the frictional engagement, such rotation of the locking ring being further and positively prevented by the engagement of the nuts with the recesses 17^a of the ring 17.

Having thus described my invention what I claim is:—

1. A collapsible mandrel for use in manufacturing pneumatic tires, comprising a hub member, a core segment rigidly carried thereby, a core segment hinged to each end of said first named segment, a key segment 115 cooperating with the free ends of said hinged segments, a lug projecting inwardly from said key segment and having a bifurcation, and a strut pivotally connected to said hub member and having its other end 120 detachably engaging said bifurcation.

2. A collapsible mandrel for use in manufacturing pneumatic tires, comprising a hub member, a core segment rigidly carried thereby, a core segment hinged to each end 125 of said first named segment, a key segment cooperating with the free ends of said hinged segments, a lug projecting inwardly from said key segment and having a bifurcation, a strut pivotally connected to said 130

hub member and having its other end detachably engaging said bifurcation, and a handle member having means for locking said end in said bifurcation.

5. 3. A collapsible mandrel for use in manufacturing pneumatic tires, comprising a hub member, a core segment rigidly carried thereby, a core segment hinged to each end of said first named segment, a key segment 10 cooperating with the free ends of said hinged segments, a lug projecting inwardly from said key segment and having a bifurcation, a strut pivotally connected to said hub member, and having its other end detachably engaging said bifurcation, a handle member carried at one side of said lug, and locking means for said strut controlled by said handle.

4. A collapsible mandrel for use in manufacturing pneumatic tires, comprising a hub member, a core segment rigidly carried thereby, a core segment hinged to each end of said first named segments, a key segment 20 cooperating with the free ends of said hinged segments, a lug projecting inwardly from said key segment and having a bifurcation, a strut pivotally connected to said hub member and having its other end detachably engaging said bifurcation, said lug 30 having an opening through one of the walls of the bifurcated portion, a spring pressed locking pin located in said opening for engaging an opening in the strut, and a handle member connected in said pin.

35. 5. A collapsible mandrel for use in manufacturing pneumatic tires, comprising a hub member, a core segment rigidly carried thereby, a core segment hinged to each end of said first named segments, a key segment 40 cooperating with the free ends of said hinged segments, a lug projecting inwardly from said key segment and having a bifurcation, a strut pivotally connected to said hub member and having its other end detachably 45 engaging said bifurcation, a bushing carried by one of the bifurcated portions of the lug and having a segmental portion, a handle member having a cooperating segmental portion, and a locking pin carried by said 50 handle member for engaging said strut.

6. In apparatus of the class described, a hub member, rigid arms carried thereby having laterally offset portions, a core section rigidly secured to said offset portions, core 55 sections having ends hinged to the ends of said first named portions and having free ends, a key section co-operating with said free ends, and detachable means for holding said key section in position, said hub and 60 said arms lying wholly to one side of the plane of the core, whereby the space within the core is entirely unobstructed.

7. In apparatus of the class described, a hub member, rigid arms carried thereby 65 having laterally offset portions, a core sec-

tion rigidly secured to said offset portions, core sections having ends hinged to the ends of said first named portions and having free ends, a key section co-operating with said free ends and detachable means for connecting said key section to said hub, said hub and said arms lying wholly to one side of the plane of the core, whereby the space within the core is entirely unobstructed. 70

8. In apparatus of the class described, a hub section, rigid arms carried thereby having web shaped offset portions, a core section having slots to receive said webs, said webs projecting from the ends of said slots, and said core section being rigidly secured 75 to said webs, a pair of complementary sections having slots in their ends to receive the projecting portions of said webs, and said complementary sections being hinged to said webs, a key section co-operating with said complementary sections, and means for detachably securing said key section in place. 80

9. In apparatus of the class described, a hub section, rigid arms carried thereby having web shaped offset portions, a core section having slots to receive said webs, said webs projecting from the ends of said slots, and said core section being rigidly secured 90 to said webs, a pair of complementary sections having slots in their ends to receive the projecting portions of said webs, said webs having portions lying inside of the inner edge of the complementary core sections, and said complementary core sections having inwardly projecting lugs embracing 95 said web portions, hinge pins passing through said lugs and web portions, and a key section co-operating with said complementary sections. 100

10. In combination, a hollow hub, a mandrel carried thereby, a supporting spindle having a collar to fit said hub, said hub and said collar having abutting portions provided with inter-engaging means to prevent relative rotation, and means for detachably locking said hub and collar together. 105

11. In combination, a hollow hub, a mandrel carried thereby, a supporting spindle having a collar to fit said hub, said hub and said collar having outwardly projecting 110 abutting flanges provided with inter-engaging means to prevent relative rotation, one of said flanges having spaced peripheral lugs, and a clamping ring rotatably mounted on the other flange and having inwardly 115 extending projections overlying said peripheral lugs. 120

12. In combination, a hollow hub, a mandrel carried thereby, a supporting spindle having a collar to fit said hub, said hub and said collar having outwardly projecting 125 abutting flanges provided with inter-engaging means to prevent relative rotation, one of said flanges having spaced peripheral lugs, a clamping ring rotatably mounted on 130

the other flange and having inwardly extending projections overlying said peripheral lugs, bolts passing through transverse openings in said ring outside the ends of the flange on said collar, and nuts on said bolts, and a retaining ring removably secured to said clamping ring and overlying the ex-

posed face of said flange on the collar, said retaining ring having recesses to receive said nuts.

10

In testimony whereof, I affix my signature.

HARVEY F. MARANVILLE.
